UNITED STATES PATENT OFFICE.

RUFUS R. ROSS, OF DETROIT, MICHIGAN, ASSIGNOR TO DETROIT SPECIALTY PRODUCTS CORPORATION, OF DETROIT, MICHIGAN, A CORPORATION OF DELAWARE.

CARBURETOR ATTACHMENT.

Application filed May 13, 1926. Serial No. 108,814.

This application is a continuation in part of my application filed May 3, 1924, Serial No. 744,120, allowed Aug. 7, 1926.

It is a well known fact that if water, vapor or steam is introduced into the cylinders or combustion chambers of an internal combustion engine that carbonizing will be reduced to a minimum and that the addition of steam and water vapor to an explosive mixture places it in better condition for combustion in the engine. It is also a well known fact that the introduction of air is beneficial and increases the volume of fuel, while oil vapor provides better lubrication and contributes towards better combustion, especially when certain fuels are used.

The primary object of my invention is to introduce steam, air, water and oil into the fuel supply system of an internal combustion engine and this may be accomplished by an attachment to the carbureting device of the engine or to the intake manifold connection thereof.

Another object of my invention is to utilize the exhaust of an internal combustion engine for heating the fuel supply to said engine, so as to place the fuel in better condition for combustion purposes.

The above and other objects are attained by a mechanical construction that will be hereinafter specifically described, and then claimed, and reference will now be had to the drawings wherein.

Figure 1 is a side elevation of an internal combustion engine equipped with my attachment;

Fig. 2 is a vertical sectional view of the manifold connection;

Fig. 3 is a longitudinal sectional view of an attachment to the air intake of a carburetor, and

Fig. 4 is a cross sectional view of the same.

Considering Figs. 1 and 2, I show an internal combustion engine 1 having a crank case 2, an exhaust manifold 3, an intake manifold 4, a carburetor 5, a throttle 6 and a pedal and bell crank arrangement 7 connected to the throttle and operable at a footboard 8 arranged below a dash 9, both of which may form part of an automobile (not shown).

Interposed between the carburetor 5 and the intake manifold 4 is the lower angular end 10 of a vertically disposed jacket 11, said jacket extending upwardly at the outer side

of the intake manifold 4. The upper end of the jacket terminates in a cylinder head 12 having a connection 13 with the exhaust manifold 3 and the lower end of the jacket 11 has another connection 14 with the exhaust manifold 3 so that the burned gases may circulate through the jacket for fuel heating purposes.

In the jacket 12 and suitably spaced from the walls thereof is a conduit 15 which extends throughout the length of the jacket and has its lower end communicating with the carburetor 5 by a series of upper and lower openings 16. These openings permit fuel to pass through the lower end of the conduit and also upwardly in the conduit to a mixing chamber 17 located within the head 12.

In the conduit 15 are two throttles 18 and 19, the former being connected, as at 20, to the throttle 6 so as to be operable thereby. The throttle 19 has an operating rod 21 extending to the dash 9 so that the supply of fuel to the mixing chamber 17 may be controlled independent of the throttles 6 and 18.

Suitably mounted above the engine 1 is a water reservoir 22 having a filling connection 23, a safety valve 24, and the gauge 25. This water reservoir is surrounded by a jacket 26 connected by pipes 27 to the exhaust manifold 3, whereby burned or exhaust gases may be utilized for heating the water within the reservoir 22 to generate steam, which is conducted from the top of the water tank 22 by a pipe 28 to the mixing chamber 17. An ordinary shut-off valve 29 may control the supply of steam through the pipe 28 to the mixing chamber 17.

The bottom of the reservoir 22 is connected by a pipe 30 to the mixing chamber 17 and this pipe is equipped with a valve 31 having an operating rod 32 extending to the dash 9. The valve 31 may be set to permit of a quantity of hot water entering the mixing chamber.

A pipe 33 connects the crank case 2 to the mixing chamber 17, said pipe having a conventional form of shut-off valve 34. This pipe and its valve permits of oil vapor entering the mixing chamber.

A valve equipped air supply pipe 35 is connected to the mixing chamber 17 so that a desired quantity of air may enter the mixing chamber and it is in this chamber that air, steam, water and oil vapor may be heat-

ed and commingled with the usual supply of fuel from the carburetor 5.

Instead of supporting the device between the carburetor and the intake manifold 4, I may mount a somewhat similar device on the air intake connection 36 of the carburetor 5, in which instance I provide the air intake connection 36 with a throttle 37. The device includes a jacket 38 and a mixing chamber 39, with the exception that the head 38 has an air passage 40 through the mixing chamber 39 to the air intake connection 36 of the carburetor. The mixing chamber 39 has the same supply connections as the mixing chamber 17, and the head 38 has substantially the same connections as the head 12. The head 38 is attached to the air intake connection 36 by a clamping ring 41, and as the air is drawn into the carburetor 20 the heated oil vapor, steam and water will also be carried therein to commingle with the usual atomized fuel supplied by the carburetor 5.

Under certain conditions the throttle 37 can be closed so that the engine can be used without my attachment, and while in the drawings there are illustrated the preferred embodiments of my invention, it is to be understood that the structural elements are 30 susceptible to such variations and modifica-

tions as fall within the scope of the appended claims.

What I claim is:—

1. The combination with an internal combustion engine having a crank case, intake and exhaust manifolds, and a carburetor adapted to supply fuel to the engine intake manifold, said carburetor having an air intake connection, of a head connected to the air intake connection of said carburetor, a mixing chamber in said head, said head having an air passage through said mixing chamber to the air intake connection of said carburetor, connections between said head and the exhaust manifold so that the exhaust gases may circulate in said head and heat said mixing chamber, a steam generator, a connection between said steam generator and said mixing chamber so that steam may be supplied to said mixing chamber, and a connection between said mixing chamber and the engine crank case so that oil vapor may be supplied to the mixing chamber.

2. The combination called for in claim 1, and a connection between said mixing chamber and said steam generator so that water may be admitted to said mixing chamber.

In testimony whereof I affix my signature.
RUFUS R. ROSS.
